UNITED STATES PATENT OFFICE

143,079

DESIGN FOR A BILGE PUMP OR SIMILAR ARTICLE

Thomas Langan, Annapolis, Md.

Application July 17, 1945, Serial No. 120,759

Term of patent 14 years

(Cl. D65—1)

To all whom it may concern:

Be it known that I, Thomas Langan, a citizen of the United States and a resident of Annapolis, in the county of Anne Arundel and State of Maryland, have invented a new, original, and ornamental Design for a Bilge Pump or Similar Article, of which the following is a specification, reference being had to the accompanying drawings, forming part thereof, in which the bilge pump or similar article showing my new design.

I claim:

The ornamental design for a bilge pump or similar article, as shown.

THOMAS LANGAN.
